[57] CLAIM

The ornamental design for an electronic locating transmitter for lost children or the like, as shown and described.

DESCRIPTION

FIG. 1 is a perspective view of an electronic locating transmitter for lost children or the like showing my new design;

FIG. 2 is a left side elevational view thereof;

FIG. 3 is a bottom plan view thereof;

FIG. 4 is a right side elevational view thereof;

FIG. 5 is a top plan view thereof;

FIG. 6 is a rear elevational view thereof;

FIG. 7 is a front elevational view thereof.

The broken lines are shown for illustrative purposes only and form no part of the claimed design.

FIG. 1

FIG. 2

FIG. 3

FIG. 4

FIG. 5

FIG. 6

FIG. 7
